WASHING MACHINE

Paul E. Frantz, Euclid, Ohio, assignor to The
Apex Electrical Manufacturing Company,
Cleveland, Ohio, a corporation of Ohio

Application April 4, 1942, Serial No. 437,619

8 Claims. (Cl. 68—134)

This invention relates to a washing machine and more particularly an oscillating agitator for such a machine.

For a number of years domestic washing machines have included a tub for holding the clothes and washing fluid and an agitator mounted in said tub provided with means to oscillate the agitator so as to cause fluid currents and a flexing of the clothes effecting a washing thereof. Because of the moisture and temperature conditions under which the agitator was designed to operate, the industry has adopted as an agitator a cast or molded article, the material being one resistant to the detergents used in the washing, resistant to sudden temperature changes and which possessed sufficient strength to move the clothes and water to effect washing. Aluminum, zinc and similar light metals have enjoyed wide popularity in this connection and phenolic resins or like plastics have also been used to make a molded agitator. Both the light metal cast agitators and the molded agitators are ordinarily made as a single monolithic unit.

Although it is well known that sheet steel is a relatively inexpensive material and possesses sufficient strength to make a washing machine agitator, the adverse temperature, moisture and stress conditions have heretofore prevented any extensive development of an agitator made of sheet steel.

According to my invention I have provided an agitator and a method of making the same in which sheet steel is utilized to form the essential working elements of the agitator.

It is among the objects of my invention to provide an agitator having a base and outstanding blades in which the base and blades are separately formed and are so secured to the base and to each other and the finished article so covered with porcelain enamel that the finished article will be resistant to temperature conditions, the detergents employed and to the stresses set up by the operation of the agitator and will thus achieve the advantages characteristic of a cast metal agitator.

It is a further object of my invention to provide a sheet metal agitator in accordance with the preceding object in which the blades are secured to the base and are secured to each other by welding and in which the welds are so disposed that they may be effectively protected against temperature and moisture conditions.

It is a further object of my invention to provide an agitator having a sheet metal base and

sheet metal blades mounted on said base wherein the blades are connected to each other at their lower edges through the medium of the base and are connected at their upper edges by a sheet metal plate generally parallel to the base and in which the base is centrally apertured to receive a cast metal socket or adapter portion suited to mount the agitator on an oscillating agitator shaft.

10 It is a further object of my invention to provide an agitator according to the preceding object in which a tube is secured to the socket or adapter portion and extends upwardly therefrom to the upper edges of the agitator blades in a manner to prevent clothes or the like from entering between the adjacent edges of the agitator blades.

15 It is a further object of my invention to provide an agitator according to the preceding objects in which the socket or adapter portion on the upper surface of the base includes ribs or the like which are effective to prevent clothes from entering the juncture between the blades at the lower edge and the base.

20 It is a further object of my invention to provide the agitator base with radial depressions designed to cooperate with the lower edges of the blades in a manner to facilitate the porcelain enameling process and to effectively prevent a cracking of the enamel due to deflections occurring in the blade when in operation.

25 It is a further object of my invention to provide a sheet metal agitator having a base and blades wherein the base and blade portions are progressively drawn from a single piece of metal.

30 It is a further object of my invention to provide an agitator having a plurality of drawn sheet metal sections wherein each sheet metal section comprises a sector of the base and one half of each of two adjacent blades.

35 Further objects and advantages relating to economies of manufacture, simplicity in construction and long life will appear from the following description and the appended drawings, in which:

Figure 20 is a cap portion covering the upper edges of the agitator and providing means for attaching the agitator to an agitator shaft.

Referring to the drawings, the preferred form of my invention comprises an agitator such as shown in Fig. 1, having a sheet metal, conical base 6. The base is provided with a rolled bead or flange 7 at its periphery and is centrally apertured to receive a socket or adapter assembly. The base is provided with radially extending depressions 8 which are adapted to receive and position the blades 9. Each of the agitator blades are provided at their lower edges with laterally extending flanges 10 and are provided at their upper edges with co-planar tabs 11. The blades are joined to each other at their upper edges by extending the tabs 11 through apertures 12 in a small disc or plate 13. The aperture 12 is formed (see Fig. 2a) by turning the stock upwardly out of the plate to form ears 14, which ears are welded, as shown, to the tabs 11 on the blade. The flanges 10 are suitably spot welded to the base 6 and the depression 8 in the area of the welded flange is of a depth to bring the upper surface of the flange 10 into the same conical surface as the base 6. This assembly comprising five parts welded to form a unit, may be made up of relatively inexpensive light gage sheet steel and the unit is then porcelain enamelled. The enameling may be carried out in the usual way by the spraying of frit and the burning of the unit in an enameling oven.

I have found that the joining of the blades to the base in the manner above described to be particularly well suited to porcelain enameling and

that during the enameling process, the molten glass will flow satisfactorily so as to cover all welds and edges to protect the same against the moisture and detergents. During operation of the agitator there is some slight deflection of the blades 9 and by joining the blade to the base according to my invention, the porcelain enamel will not crack at the juncture between the base and the blade.

10 Referring particularly to Fig. 5, it will be observed that the depression 8 extending radially of the base is slightly wider than the flange 10 at the bottom edge of the blade 9 so that the molten glass will not bridge the gap between the edges 15 of the flange and the upper surface of the base. This arrangement provides a coating of porcelain enamel of substantially uniform thickness over all of the exposed surfaces around the juncture between the blades and base and the cracking of 20 the enamel is thereby eliminated.

The slight deflection in the blade 9 due to impact against the clothes and water during operation, may be accommodated by the curve in the bend indicated at 9a. The character of the 25 curve or bend at 9a is such that there is no substantial accumulation of porcelain between the bend at 9a and the upper surface of the base 6. Thus the normal operating loads on the agitator are ineffective to break the porcelain bond which 30 covers all of the exposed surfaces substantially uniformly.

Those familiar with the porcelain enameling art will appreciate that any method of joining the base to the blades which would permit a 35 cracking of the porcelain enameling at this point, would render the agitator impractical because the water and detergents would attack the exposed metal and bring about the formation of rust which would soil the clothes and destroy the 40 utility of the agitator.

The socket or adapter comprises a lower portion 15, which has a maximum diameter exceeding the diameter of the aperture in the base and a stem portion which projects upwardly 45 through the aperture and a retaining shoulder portion 16 which telescopes over the said projecting stem. The two portions 15 and 16 are held in their assembled relation as shown best in Fig. 2 by screws 17 extending upwardly 50 through holes around the periphery of the base aperture and into threaded openings in the portion 16. Suitable gasket material 18 is clamped between the upper and lower portions 15 and 16 and the clamping effect through the gasket material, combined with the fastening screws 17, is effective to transmit the torque of the agitator shaft 19 to the base 6 without chipping or flexing the base structure.

60 A tube 20, preferably formed of brass or of plated ferrous metal, extends substantially the full height of the agitator and is anchored at its lower end by threaded engagement with the stem of the socket or adapter member. At the upper end of the tube 20 it projects through an aperture centrally formed in the plate 13, thence through a rubber block 21 and through a cover plate 22. The upper end of the tube 20 is threaded to receive a clamping nut 24 which serves to draw the cover plate downwardly and compress the rubber block 21 between the plates 22 and 13. A large cupped washer 25 is arranged in the extreme end of the tube and an elongated agitator screw 26 extends downwardly through 65 the tube 20 and into the top of the agitator shaft 70

19 so as to securely hold the entire assembly on the agitator shaft 19.

The body of the portion 16 of the socket member has a diameter corresponding to the space provided by the dihedral angle opening between the blades adjacent the base. This diameter or distance is indicated at X in Fig. 6. It is obvious that the portion 16 of the socket must be inserted through this dihedral angle opening, before the stem portion of the member 15 is projected upwardly through the base during assembly. To prevent threads or portions of the clothes being washed from entering the space between the portion 16 and the edges of the blades 9, the member 16 is provided with ribs 28 which correspond in number to the number of blades.

In order to position the portion 16, it is necessary to advance the portion through the dihedral opening as indicated diagrammatically in Fig. 6. The member 16 is shown in full lines in its initial position A; that is, where one of the ribs 28 is in engagement with the adjacent face of one of the blades 9. From this position the portion 16 may be rotated (but not shifted laterally) to the dotted line position B and this leaves but one of the ribs outside of the dihedral angle. The portion 16 is then advanced to the position C where one of the ribs 28 is against the edge of a blade 9. This position is indicated in the dot and dash line C of Fig. 6. From this last-named position, the portion 16 may be shifted laterally and rotated to bring the ribs 28 into coplaner position with the blades 9 and thus close the dihedral opening. The screws 17 may then be inserted and drawn up to lock the parts in proper position. The parts are shown in their proper assembled position in Fig. 4.

That form of the agitator shown in Figs. 17 to 20 corresponds to the preferred form of Fig. 1 in the mounting of the blades on the base. In the modification of Fig. 17, the base 30 is also radially depressed at intervals to receive the flange 31 of blade 32. In this modification, however, the tube heretofore provided to prevent clothes from entering the juncture between the blades is eliminated by the use of integrally formed sectors 33 on the blade. The sectors are bent out of the plane of the blade into an arcuate curve of about 120 degrees and are then formed as at 34 to become coplaner with an adjacent blade 32. The opening in the dihedral angle between the blades at their juncture with the base is preferably closed with a socket or adapter member as in the preferred embodiment.

An agitator screw such as 35 extends downwardly within the tube formed by the blade juncture portion 33 and said agitator screw fixes the agitator in position on the agitator shaft substantially as screw 26 in the preferred embodiment. Since in the modification of Fig. 17, the blades are joined to each other substantially throughout the vertical height by spot welding the portions 34, it is unnecessary to provide a top plate connection as in the preferred embodiment. The upper edges of the agitator are preferably covered by a cap member 36 and suitable gasket material 37 is inserted between the cap and the upper edges of the blades 32. It will be understood that the modification of Fig. 17 possesses the advantages of the preferred form with respect to the porcelain enameling and the distribution of the loads and flexure during operation.

In certain forms of agitators, particularly those

which do not require a blade having substantial vertical extent, the agitator may be drawn of sheet steel and the base and blades formed as a unitary structure. This is effected according to my invention by taking a single sheet of metal and first drawing a cone such as the sheet metal cone 40 of Fig. 7. The cone is then depressed on three sides to form the blank shown as at 41 in Fig. 8. A further drawing operation is then performed on the blank 41 to increase the height of the blade and produce the blank shown at 42 in Fig. 9. The last described operation results in a conical base 43, a tubular section 44 and the integrally formed blades 45. The apex of the blank may then be cut off on the line indicated at 46 and a tubular section 47 welded to the blank 42. Then a disc 48 is welded at 49 inside of the base portion of the agitator which disc is suitably apertured to receive the stem of an adapter 50 and is provided with holes around the aperture to receive the bolts or like fasteners 51.

Prior to the assembly of the agitator on the socket or adapter 50, the entire unit is porcelain enameled so as to render the same resistant to temperature and moisture conditions occurring during operation with the socket member 50 attached to the disc 48 at the underside of the agitator. The porcelain enameled unit may be assembled on an agitator shaft 52 and retained thereon by a screw 53 extending downwardly through an agitator cap 54.

The foregoing description has covered the method of making multi-part agitators of sheet metal having relatively high blade structures and also the one-piece drawn sheet metal porcelain agitator having relatively low agitator blades.

According to my invention, an agitator intermediate said high and low blade types may be formed by the combination of the two steps; namely deep drawing and welding. I have shown such modifications in Figs. 11 to 16, inclusive. Fig. 11 shows a blank 60 which is drawn to provide a part of a conical base 61, a sector of a center post 62 and wings 63 and 64. The wings are adapted to form one side of adjacent blade sections so that three drawn sectors or blanks such as 60 may be assembled as shown in Fig. 13 to form a complete agitator unit. The mating edges of the three sectors are welded to each other and the welded assembly then porcelain-enameling throughout. Figs. 11 to 15, inclusive, show sectors having inturned flanges adapted to be secured to each other prior to porcelain-enameling, whereas Fig. 16 shows a similar construction wherein the mating edges abut each other so as to provide for a butt-welded joint between the sectors. The sectors in the form of Fig. 16 are indicated at 60a. The welded unit made up of three sectors is preferably provided with a sheet metal conical base 65 which is welded along its periphery to the conical base sectors 61. The base 65 is centrally apertured and is provided with a socket member 66 adapted to fit the upper end of an agitator shaft 67. The upper end of the agitator is provided with a cap 68 apertured to receive an agitator screw 69 which extends downwardly to the agitator shaft and holds the unit in fixed position on the shaft.

Although I have described a preferred form and modified forms of my invention in considerable detail, it will be understood that numerous modifications may be made therein without departing from the scope of the invention as defined in the following claims.

Having thus described my invention, what I claim is:

1. An agitator comprising a sheet metal, conical base, a plurality of sheet metal blades, each blade having a greater radial extent at the bottom than at the top, means to secure the bottom portions of said blade to said base comprising a flange normal to the plane of the blade welded to said base, means to secure the top portions of said blades to each other comprising integral tabs coplanar with the blades, a disc apertured to receive the tab on each blade and secured to said tab and a porcelain enameled covering for said base, blades and connecting means.

2. An agitator comprising a centrally apertured sheet metal base, a plurality of flat sheet metal blades having flanges at their lower edges, radially extending depressions formed in said base proportioned to receive said flanges, a plate joining said blades to each other at the upper edges of the blades, a cast metal socket member secured in the central aperture of said base, said socket member having an opening on the under side thereof to receive an agitator shaft and an agitator screw to secure the agitator to the shaft extending downwardly through said plate, through said socket and into said agitator shaft.

3. An agitator comprising a conical sheet metal base having radial depressions extending from the center thereof substantially to the periphery, a plurality of upstanding blades, means to secure said blades in said depressions comprising integrally formed flanges on the lower edges of the blade, a weld bonding said flanges to said base and a porcelain enamel coating of substantially uniform thickness covering said blades, base and flanges.

4. An agitator comprising a conical base having radially extending depressions on the upper surface thereof, upstanding blades mounted on said base having offset flanges along the lower edges thereof, said flanges arranged in said depressions and spaced slightly from the edges thereof, a porcelain enamel coating of substantially uniform thickness covering the said base, blades, flanges and the juncture between the edges of said flanges and the surface of said conical base.

5. An agitator comprising a conical sheet metal base, radially extending depressions forming said base, upstanding blades having offset flanges at their lower edges, arranged in said depressions, means to secure said flanges to said base, said base having a centrally formed aperture provided with a two-part socket member, one part of said socket member having a diameter exceeding the diameter of the aperture in the base and an

upwardly projecting stem, the other part of said socket member apertured to receive said stem and having a diameter exceeding the diameter of the aperture in said base and means connecting the two parts of said socket member to clamp the base therebetween.

6. An agitator comprising a sheet metal base, an agitator shaft socket therefor, comprising upper and lower portions clamping the base therebetween, a plurality of sheet metal blades secured to the upper surface of said base, the lower edges of said blades adjacent the center of the base being cut away to receive the upper portion of said socket member, said upper portion having ribs thereon and adapted to be moved to bring said ribs co-planar with said blades to prevent clothes from entering the space between the socket member and the cut-away portion of the blade.

7. An agitator comprising a conical sheet metal base having radially-extending depressions on the upper surface thereof, a socket receiving aperture formed centrally of the base, upstanding blades having flanges along their lower edges welded in said depressions, a socket member having upper and lower parts arranged to clamp said base around said aperture, the lower part of said socket member having a tapered opening adapted to receive an agitator shaft at its lower side and having a cylindrical opening at its upper side, said blades having vertical edges spaced from each other above said socket member and a vertical tube proportioned to fill the space between the vertical edges of adjacent blades mounted in said cylindrical opening of said socket member and means within the tube to anchor the agitator assembly to an agitator shaft.

8. An agitator comprising a conical sheet metal base having radially extending flat-bottomed depressions formed therein, a plurality of upright sheet metal blades mounted on said base, means to secure the blades to the base comprising integrally formed flanges on the lower edge of the blades, said flanges bonded by a weld to said base in the bottom of said depressions, said flanges having a width less than the width of the radially extending depressions and a porcelain enamel covering for said blades and base, said covering having a thickness characteristic so that it is insufficient to bridge the gap with porcelain between the upper surface of the flanges and the upper surface of the base whereby the connection between the base and blades is resistant to porcelain cracking failure at the juncture between the base and blades.

PAUL E. FRANTZ.
